UNITED STATES PATENT OFFICE.

JOB J. SMITH, OF FRANKFORT, KENTUCKY.

CHURN-MOTOR.

SPECIFICATION forming part of Letters Patent No. 236,964, dated January 25, 1881.

Application filed December 16, 1880. (No model.)

To all whom it may concern:

Be it known that I, JOB J. SMITH, of Frankfort, in the county of Franklin and State of Kentucky, have invented certain new and useful Improvements in Churn-Motors; and I do hereby declare that the following is a full, clear, and exact description of the invention, which will enable others skilled in the art to which it appertains to make and use the same, reference being had to the accompanying drawings, which form a part of this specification.

Figure 1 is a perspective view, and Fig. 2 is a vertical longitudinal sectional view.

Similar letters of reference indicate corresponding parts in both figures.

This invention relates to churn-motors; and it consists in certain improvements in the construction of the same, which will be herein-after fully described, and particularly pointed out in the claims.

In the drawings hereto annexed, A represents an upright fixed in a base, B, and carrying a longitudinal top or cross piece, C. The latter is provided at its rear end with a slot, 25 D, to accommodate the pitman E, which latter connects a crank, F, upon a shaft, G, journaled transversely upon the top piece, with the end of a treadle, H, suitably mounted upon the base. The shaft G carries at one end a fly- 30 wheel, I, and at the other end a disk, J.

The front end of the top piece, C, is provided with a horizontal slot, K, in which is mounted, upon a vertical pin or axle, a wheel or disk, L, provided with a laterally-extending 35 arm, M.

N is a short arm or connecting-piece pivoted to arm M, and connected by a hinge-joint, O, to a rod, P, the other end of which is pivoted upon the face of the disk J. The rotary motion of the latter is thus, it will be seen, converted into an oscillating motion, which is conveyed to the horizontal wheel or disk L.

Disk L is provided upon diametrically opposite sides with horizontal or semi-annual 45 grooves Q R, one of which is near the upper and the other near the lower edge of the disk. At its rear end, or just between the rear termination of the grooves Q R, the disk is provided with a notch, S, in which are secured 50 two hooks or buttons, T T, which, by making the notch sufficiently large, are readily accessible.

U U are belts or bands provided with holes

or slots, by which they may be adjusted upon the hooks or buttons, from whence they pass 55 around the sides of the disk, being adjusted in the grooves Q R and to the front end of the top piece, C. The latter is provided with a suitable bearing for the vertical dasher-shaft V, which is provided with a drum, W, around 60 which the belts U are wound in opposite directions, and to which they are permanently attached.

The dasher X may be of any suitable construction.

From the foregoing description, taken in connection with the drawings hereto annexed, the operation and advantages of my invention will be readily understood. The mechanism, which is worked by foot-power, imparts 70 to the dasher an oscillating motion, which is conceded to be very desirable. To remove the dasher, which it is necessary to do when the churn is to be placed in position or removed, it is only necessary to unbutton the belts U, 75 which it is manifestly easy to do. The general construction of my improved churn-motor is simple and inexpensive, and it is easily operated.

Having thus described my invention, I claim 80 and desire to secure by Letters Patent of the United States—

1. As an improvement in churn-motors, the combination of the upright A, having cross-piece C, crank-shaft F G, pitman E, treadle H, 85 wheel or disk J, horizontal disk L, having arm M, pivoted connecting-piece N, connecting-rod P, and means for conveying motion from the disk L to the dasher, substantially as and for the purpose herein set forth.

2. The combination of the dasher-shaft V, having drum W, belts or bands U U, secured to said drum and wound in opposite directions around the same, horizontal disk L, having grooves Q R, notch S, and hooks or buttons T T, and mechanism for imparting to the disk L an oscillating motion, substantially as and for the purpose set forth.

In testimony that I claim the foregoing as my own I have hereto affixed my signature in 100 presence of two witnesses.

JOB J. SMITH.

Witnesses:

ROBERT SANFORD,
F. R. SMITH.
